Application October 4, 1935, Serial No. 43,617
In Germany October 8, 1934

14 Claims. (Cl. 72—66)

The present invention relates to an improved reinforced concrete ceiling or floor structure, the individual constructional elements of which, for the purpose of forming a monolithic structure, 5 can be assembled and monolithically combined without any form work.

Quick setting Portland cement is used and the constructional elements made in accordance with the present invention allow the construction work 10 to advance very rapidly, since at first, on running up the walls, only the light-weight profiled steel girders need be laid down. The constructional elements in the form of previously cast slabs or tiles of chambered character can be put in place 15 at a later period, even, if so desired, after the roof has been placed on, at which time the investing concrete is poured around the girders and about the slabs, which, obviously, is of great advantage during inclement weather.

20 The emplaced light-profiles can be used in the course of the construction work as stage or scaffolding, and since such profiled girders can be had anywhere from standardized stock in length up to 30 meters, they can readily be procured as needed.

25 The fundamental difference between the old style armored concrete ceiling and the new construction is that the latter can be erected without the use of any form work, without any top or bottom application of concrete, and with an already formed surface producing a plane lower face; and that the ceiling can be laid down at any time, after the walls, and if desired, after the roof, have been erected.

30 In previous constructions of this character each reinforced ceiling or floor had to be placed or poured as soon as the walls had reached the required height, and had then to be allowed to set before the work on the walls could be resumed. 35 This, obviously, caused considerable loss of time. The present invention overcomes this objection.

35 The new ceiling can readily be built into old buildings, since, after taking out the old ceilings, only the supporting recesses for the light-weight profile girders need be cut into the walls.

40 In the accompanying drawings:—

45 Fig. 1 is an isometric perspective view, partly in section, of two hollow blocks or tiles and a supporting I-beam, as arranged in one manner to form a portion of a floor or ceiling embodying my invention.

50 Fig. 2 is a vertical transverse section through a portion of a completed floor or ceiling formed in accordance with my invention.

55 Fig. 3 is a top plan view of a complete tile and

portions of adjacent tiles of a row showing the manner in which the tiles are disposed in a longitudinal row in accordance with the arrangement shown in Figs. 1 and 2.

Fig. 4 is a vertical longitudinal section on the 5 line 4—4 of Fig. 3.

Fig. 5 is a view in end elevation of the tiles shown in Fig. 3.

Fig. 6 is an isometric perspective view of one of the tiles looking toward one side thereof. 10

Fig. 7 is a similar view of the tile looking toward the opposite side thereof.

Fig. 8 is a view similar to Fig. 3 showing a different arrangement of the tiles in a row.

Fig. 9 is a vertical transverse section on line 15 3—9 of Fig. 8.

Fig. 10 is a vertical longitudinal section on line 10—10 of Fig. 8.

Fig. 11 is a fragmentary perspective view of a tile showing a modification. 20

In constructing a floor or ceiling according to my invention, standardized spaced, parallel I-beams or purlines 1, preferably of the built-up or fabricated type, are placed in position by fitting their ends in suitable receiving recesses provided 25 in opposed walls of the building. In the spaces between opposed sides of adjacent beams are arranged rows 2 of hollow slabs or tiles 3 formed of any suitable material. Each of these tiles is of rectangular or oblong rectangular form, the tiles 30 shown being of oblong rectangular form, and each tile comprises a body portion having a straight or plane bottom wall 4, an arched top wall 5, a straight or plane crown wall 6, end walls 7 and 8 and a side wall 9. In order to secure desired 35 lightness in weight the tile body and its crown wall are hollowed out by providing the same with sets of cavities 10 and 11, which cavities open to the exterior through one side of the tile and are closed at the opposite side of the tile by the 40 straight or plane side wall 9.

As shown, the crown wall 6 is shorter than the top wall 5 and has its ends 12 and 13 terminating short or inwardly of the end walls 7 and 8, thus forming transverse shoulders 14 and 15 between 45 the ends of the crown wall and the respective walls 7 and 8 at the opposite ends of the tile. The ends 12 and 13 are undercut or beveled downward and inwardly toward the inner edges of the shoulders 14 and 15, for an anchorage action in the 50 binding cement or concrete as hereinafter described, and the shoulders 14 and 15 slope outwardly and downwardly from the ends 12 and 13 to the walls 7 and 8 so as to form angular or substantially V-shaped recesses at the ends of the 55

tile above the plane of the end walls 7 and 8. A feature of my invention consists in spacing the said ends 12 and 13 of the crown wall or portion 6 from the end walls 7 and 8, the end 12 being placed 5 at a somewhat greater distance inwardly from the wall 7 than the recess formed by the end 13 from the wall 8, with the effect of making the end 12 and shoulder 14 deeper than the recess formed by the end 13 and shoulder 15 and increasing the 10 depth and width of the shoulder 14 with respect to the shoulder 15 and consequently disposing the shoulder 14 at a lower horizontal level than the shoulder 15.

Formed on the respective end walls of each 15 tile are supporting lugs or projections 16 and 17, the lower surfaces of which are disposed at the same level and the upper surfaces of which intersect and are beveled to conform with the slope of the shoulders 14 and 15, the lug 16 thus 20 being smaller or of less vertical extent than the lug 17. Each lug has its lower surface undercut or recessed or otherwise suitably shaped, as at 18, to receive and engage or rest upon a lower flange of a supporting beam 1, and beneath the 25 lugs 16 and 17 the walls 7 and 8 are undercut or recessed to provide supporting flanges or ledges 19. Similarly the closed side 9 of each tile is undercut at its base to form a V-shaped recess 20 and supporting ledge or flange 21. The 30 longitudinal side edges of the crown wall 6 may also be undercut or rabbeted to form V-shaped recesses 22.

In Figs. 1 to 5, inclusive, I have shown a preferred manner of arranging the tiles to form a 35 floor or ceiling in accordance with my invention. As shown, pairs of tiles 3 in each row, at spaced intervals in the row, in which the tiles extend side by side between two adjacent I-beams 1, are arranged so that the closed sides of the tiles 40 of each pair abut and so that the open sides of such tiles face outwardly or reversely and abut against the open sides of the next adjacent tiles in the row, the closed sides of which adjacent tiles face outwardly so as to abut against the 45 closed sides of the next succeeding tiles in the row and so on throughout the row along the lengths of the I-beams and between the opposite walls of the building between which the I-beams extend. The tiles of the row so disposed 50 are supported by engagement of the notched lower faces of their lugs 16 and 17 with the edges of the lower flanges of the I-beams. When the tiles of two contiguous rows are thus supported by the oppositely extending lower flanges of an 55 intervening I-beam, a space or channel 23 is formed by the opposed ends of the rows of tiles which embodies a relatively wide and deep upper portion disposed above the plane of the supporting lugs of the tiles and a relatively narrower and shallower portion below the plane of the supporting lugs of the tiles, which portions of the space or channel are connected by passages arranged between the lateral and outer faces of the supporting lugs. In this channel 60 60 or space the I-beam 1 is disposed so that its top and bottom flanges lie wholly within the channel and respectively below and above the upper faces of the tiles. Bridge plates 24 are then placed in position to close the bottom portion of the channel, which plates are provided at their opposite side edges with flanges 25 to 70 rest upon the flanges 19 of the tiles. Each bridge plate 24 is of a length equal to the width of a tile and of a width conforming substantially to 75 the distance between the flanges 19. Preferably

each bridge plate 24 is provided with a concaved upper face and a plane or straight lower face, which latter lies, when the bridge plate is placed in position, in the plane of the faces of the bottom walls 4 of the tiles and forms therewith a flat and substantially smooth ceiling surface. After all the plates 24 are arranged to close the bottom of the channel 23, liquid grout or a fluid concrete mix is poured into the channel from the top, until the channel is completely filled 10 up to the level of the top surfaces of the tiles. When this mix has set a monolithic structure is presented, since the beam 1 and lugs 16 and 17 of the tiles are solidly invested in the concrete and the bridge plates 24 solidly bound in 15 position. When the work of laying a floor in this manner is completed a strong and durable floor is provided, which may be used without any additional cement or finishing coats for either its upper or floor surface or bottom or ceiling 20 surface, unless it is desired to make these of finely finished character, and no further application of cement for strengthening purposes is required except under special conditions, as when specially heavy loads are to be supported or 25 specially heavy shocks or strains sustained. It will, of course, be understood that as a final operation, grout or other sealing means may be introduced to close the spaces between the recesses 20 and 22 to unite the opposed surfaces 30 of the tiles, and that where necessary joints or gaps between surfaces may be closed by a pointing up operation.

In practice, the lower portion of the channel 35 23 is made of such depth and the bridge plates 24 and such portion of the channel of such width as to adapt the bridge plates 24 to be fitted in place from below and between the flanges 19, by inserting them upwardly in an inclined position or at an angle, which is permitted by the 40 depth of the recess, until fully inserted, and then tilting them to a horizontal position so as to bring their flanges 25 into position to rest upon the flanges 19. This adapts the bridge plates to be placed in position after the rows of tiles have 45 been set in place, and is a great convenience and saving in time and labor over any other method.

It will be observed that by the described construction and arrangement of the surfaces 12, 13, 14 and 15 and the supporting lugs 16 and 50 17 of the tiles, flow passages are provided for the free downward flow of the concrete mix to all portions of the channel, the mix introduced into the top portion of the channel flowing downwardly to the lower portion of the channel 55 through the passages between the lateral faces of the lugs and downwardly over the sloping surfaces of the shoulders 14 and 15 and through the passages between the outer faces of the lugs, whereby a complete and rapid filling of the channel with the mix and investment of all parts therein in the said mix is ensured. It will also be apparent that as the shoulders 14 and 15 and lugs 16 and 17 are arranged alternately at different levels in the channel along each row of 60 tiles, a staggered arrangement of horizontal and vertical abutment surfaces is provided, whereby the tiles are mechanically interlocked in the said cement or concrete against any possibility of shifting in any direction. The construction described also ensures that the I-beams will be 65 completely invested in the concrete and thus reinforced and protected from rust.

In practice the concrete filling may be armored or reinforced in any suitable manner, as by weld- 70 75

ing to the lower flanges of the I-beam reinforcing rods or ribs 26, or placing steel wire loops or stirrups 27 at intervals about the beams, whereby reinforcing elements will not only be provided for the concrete, but the lower flange of the beam will be additionally strengthened by suspension from the upper flange thereof, and reinforcing rods 28 or the like may be arranged in the channel so as to be invested in the concrete filling at points desired. Conducting pipes, electric cables and the like can be extended through a channel formed by the recesses 29 either by inserting them from an end of the row of set up tiles or by chiseling off the flanges 21 after the tiles are laid, placing the conductor in position in the channel and then sealing the latter by means of concrete or other sealing material. Conductors of this character may also be extended through the channel either below the bottom of the I-beam or on opposite sides of the upper portion thereof so as to be bound in place when the concrete is introduced.

It will be seen from the foregoing that the tiles 3 have an asymmetrical conformation as to their supporting ends, the end faces and lugs at such ends differing in dimensions from each other. This construction of the tiles allows the tiles to be assembled so that the differently dimensioned faces and the lugs 16 and 17 will alternate in arrangement at each side of the row of tiles, to stagger them for a more secure anchorage in the concrete filling. The closing of each tile by a wall 9 at one side allows the first and last tiles of a row to be placed with their closed sides toward the walls of the building so as to avoid the necessity of using extra closing means at the emplacement points to seal the tiles against entrance of moisture or to prevent the entrance of concrete into the cavities of the tiles. It will, of course, be understood that instead of profile tiles or fabricated tiles, ordinary rolled I-beams may be employed, in which event the engaging faces of the lugs 16 and 17 will be properly formed to rest upon the bottom flanges thereof. The construction of the tiles and bridge plates, as will be evident from the foregoing description and disclosure in the drawings, adapts a floor or ceiling to be constructed in accordance with my invention without the use of any framing or false work whatever, as the emplaced I-beams or girders serve the function of the framing or scaffolding, and the tiles and bridge plate may be placed in position at any time during the period of erection of the building and this work left in abeyance, if desired, until the roof has been placed, thus allowing the floor and ceiling work to be carried out while the interior of the building and workmen are protected from the action of the elements. The novel construction of these parts also obviously enables the other advantages previously set forth herein to be gained in a convenient, ready and economical manner.

In Figs. 8, 9 and 10 I have shown a floor or ceiling construction embodying a different arrangement of tiles and bridge plates from that shown in Figs. 1 to 5, inclusive. With this arrangement shown in Figs. 8 to 10, inclusive, the tiles of a row are arranged in spaced pairs, with the open sides of the tiles of each pair abutting and the closed sides of such tiles directed outwardly and facing the closed sides of the tiles of adjacent pairs on opposite sides thereof, this arrangement producing transverse chambers or spaces 28 between the pairs of tiles. These spaces are closed

at their bottom portions by bridge plates 24a of the same size and construction as the plates 24, which are also employed, as in Figs. 1 to 5, inclusive, to close the bottoms of the channels 23, as shown in Fig. 9, the dimensions of the bridge plates adapting them to be employed for both purposes. These chambers or spaces 28, like the channels 23, may be closed by a filling of concrete or other sealing material if desired, or may be only partially filled to an extent sufficient to 10 lock the bridge plates 24a in position.

It will, of course, be understood that the lugs 16 and 17, instead of being arranged centrally of the ends of the tiles, may be disposed on the ends at any point between the sides of the tiles. Fig. 15 11 shows a modification in which, for example, a supporting lug 18' is disposed on the end of a tile adjacent to one side thereof.

From the foregoing description, taken in connection with the drawings, the construction, mode 20 of erection and advantages of my improved floor and ceiling structure will be readily understood without a further and extended description and it will be seen that a structure is provided which affords substantial advantages in point of simplicity, ease and economy of erection, strength and durability. While the structure disclosed is preferred, it will, of course, be understood that changes in the form, construction and arrangement of parts may be made within the scope of 30 the appended claims, without departing from the spirit or sacrificing any of the advantages of the invention.

What I claim is:—

1. A tile of the character and for the purpose 35 described comprising a body having asymmetrical end portions each provided with a lower face and an upper face longitudinally spaced from each other, and a supporting lug of less length than the width of the tile projecting from said lower 40 face of each end of the tile, the upper and lower faces of the respective ends of the tile being dissimilarly longitudinally spaced and the lugs upon the respective ends of the tile having their upper surfaces disposed at different horizontal levels. 45

2. A tile of the character and for the purpose 50 described comprising a body having asymmetrical end portions, each provided with an upper face, a lower face and a transverse shoulder between said faces, the upper face at one end of the tile 55 being spaced longitudinally from the lower face a greater distance than the upper face at the opposite end of the tile so as to vary the width of the shoulders at the opposite ends of the tile with respect to each other, and supporting lugs projecting from the lower faces of the ends of the tile, said lugs being of less width than the ends of the tile and having their lower surfaces disposed at the same level and their upper surfaces at different levels. 60

3. A tile of the character and for the purpose 65 described comprising a body having asymmetrical ends, each provided with an upper transverse surface, a lower transverse surface and an outwardly and downwardly inclined shoulder between said surfaces, said upper and lower surfaces at one end of the tile varying in depth and longitudinal spacing with respect to the upper and lower faces at the opposite end of the tile, and the shoulders at the opposite ends of the tile 70 varying in width with respect to each other, and beam engaging supporting lugs of less length than the ends of the tile disposed upon the lower faces of the ends of the tile and having their lower surfaces arranged at the same level, the 75

upper surfaces of said lugs being arranged at different levels and inclined to conform to and intersecting the upper inclined surfaces of the respective shoulders.

5. 4. A tile of the character and for the purpose described comprising a body having asymmetrical ends, each provided with an upper transverse surface, a lower transverse surface arranged in a plane outwardly beyond said upper transverse surface and an outwardly and downwardly inclined shoulder between said surfaces, said upper and lower surfaces at one end of the tile varying in depth and longitudinal spacing from the upper and lower faces at the opposite end of the tile, and the shoulders at the opposite ends of the tile corresponding varying in width with respect to each other, and beam engaging supporting lugs upon the lower faces of the ends of the tile of less length than the width of the ends of the tile and having upper surfaces inclined to correspond to and intersecting the inclined surfaces of the shoulders at their respective different horizontal levels.

5. A tile of the character and for the purpose described comprising a body having cavities therein opening through one side thereof, said cavities being closed by a wall at the opposite side of the body, the body being provided with asymmetrical end portions, each having an upper transverse face, a lower transverse face and an outwardly and downwardly inclined shoulder therebetween, the upper and lower faces at one end of the body being spaced longitudinally a different distance than the corresponding faces at the opposite end of the body and the shoulder at one end of the body being of greater width than the shoulder at the opposite end of the body, and beam engaging supporting lugs upon the lower faces of the ends of the body, said lugs being of less length than the ends of the body and having their upper surfaces outwardly and downwardly inclined to correspond to and intersecting the inclined upper surfaces of the shoulders at their respective different horizontal levels.

45. 6. A tile of the character and for the purpose described comprising a body having asymmetrical end portions, each provided with upper and lower undercut transverse faces and transverse shoulders between said faces, the upper face being arranged in a plane inwardly of the plane of the outer face, supporting lugs of a length less than the width of the ends of the tile formed upon the lower faces of the ends of the tile, the lugs upon the opposite ends having their upper surfaces arranged in different horizontal planes and the said shoulders and upper faces of the lugs being inclined in an outward and downward direction, and flanges upon said lower faces of the ends of the tile disposed below the lugs.

60. 7. In a floor or ceiling structure, the combination of spaced beams having supporting flanges at their lower edges, a row of tiles disposed between said beams, said tiles having asymmetrical end portions spaced from the beams, and lugs of less length than the ends of the tiles projecting therefrom and engaging the flanges of the beams, the lugs at the ends of each tile having their upper surfaces arranged at the different levels and the tiles of the row being arranged so that 65 their dissimilar lugs alternate in arrangement with each other at each side of the row and throughout the length of the row, and sealing material filling the spaces between the tiles and the beams.

75. 8. In a floor or ceiling structure, the combina-

tion of spaced flanged supporting beams, a longitudinal row of transversely arranged tiles disposed between the beams, said tiles being provided with end portions spaced from the beams and having supporting lugs projecting therefrom and 5 engaging the flanges of the beams, and flanges on the ends of the tiles below said lugs, the lugs of adjacent ends of the tiles being arranged in staggered order throughout the row with relation to each other, bridge plates resting on the flanges 10 of the tiles beneath the lugs and closing the space beneath the beam between adjacent rows of tiles, and a binding and sealing material disposed in the space between the ends of the rows of tiles and the supporting beam. 15

9. 1. In a floor or ceiling structure, the combination of spaced flanged supporting beams, a longitudinal row of tiles arranged side by side transversely between the beams, said tiles having cavities therein opening through one side 20 of the tile and closed at the opposite side of the tile, certain of said tiles having their closed sides in abutting relation, each of said tiles being provided with end portions spaced from the beams and provided with supporting lugs projecting 25 therefrom and resting upon the flanges of the beams, lugs at opposite ends of each tile having their upper surfaces disposed at different levels and said tiles being arranged so as to have their dissimilar lugs arranged in alternation and staggered order at each side of the row, and a binding 30 and sealing material between the beams and ends of the tiles.

10. In a floor or ceiling structure, the combination of spaced flanged supporting beams, a longitudinal row of tiles arranged side by side transversely between the beams, said tiles having cavities therein opening through one side of the tile and closed at the opposite side of the tile, certain of said tiles having their closed sides in 35 abutting relation, each of said tiles being provided with end portions spaced from the beams and provided with supporting lugs projecting therefrom and resting upon the flanges of the beams, lugs at opposite ends of each tile having 40 their upper surfaces disposed at different levels and said tiles being arranged so as to have their dissimilar lugs arranged in alternation and staggered order at each side of the row, bridge plates arranged beneath the bottoms of the 45 beams and engaging and closing the spaces between the rows of tiles, and a binding and sealing material between the beams and ends of the tiles.

11. In a floor or ceiling structure, an I-beam, 55 rows of tiles disposed on opposite sides of said beam, the tiles of each row having their sides in abutting relation and having their end portions provided with supporting lugs engaging the lower flanges of the I-beam and formed with 60 supporting flanges beneath said lugs, said flanges of the tiles being disposed below the bottom flanges of the beam and bridge plates adapted to be disposed to close the space between the rows of tiles beneath the beam and provided 65 with flanges to rest upon said flanges of the tiles, said bridge plates being of such dimensions as to adapt them to be inserted at an angle upwardly from below into the space below the beam and between the flanges of the tiles and pivoted into 70 supporting engagement with the latter.

12. In a floor or ceiling structure, spaced parallel I-beams, a row of tiles arranged side by side between the beams and having supporting lugs at their ends engaging the lower flanges of 75

the beams and supporting flanges beneath said lugs, the bodies of the tiles being provided with cavities opening through one side thereof and closed by a wall at the other side thereof, said tiles being arranged in spaced pairs with their open sides facing each other and their closed sides facing the closed sides of adjacent tiles of other pairs at opposite sides thereof, said sides of the tiles being provided with base supporting flanges, bridge plates engaging said flanges and closing the bottom portions of the spaces between pairs of tiles, and bridge plates arranged between the ends of the tiles and beneath the lower flange of the I-beam and resting on said flanges of the tiles beneath the supporting lugs.

13. In a floor or ceiling structure, an I-beam, rows of tiles disposed on opposite sides of the beam and having supporting lugs engaging the lower flanges of the beam and provided with supporting flanges located below the plane of the bottom of the beam, bridge plates disposed to close the space between the rows of tiles beneath the beam and in spaced relation thereto, said plates having their upper surfaces recessed, a filling of binding material between each row of

5 tiles and the adjacent side of the beam, and binding material between the bottom of the beam and rows of tiles and the bridge plates, said material seating in the recessed upper surfaces of said plates.

14. In a floor or ceiling structure, an I-beam, a row of tiles disposed on each side of the beam with their sides in abutting contact and having their ends facing the beam provided with supporting lugs resting upon the adjacent lower flange of the beam and formed below said lugs with supporting flanges disposed below the level of the beam, the lugs of adjacent tiles being horizontally spaced to provide vertical passages therebetween, binding material disposed between the sides of the beam and ends of the tiles of the rows and filling said passages, bridge plates closing the space between the rows of tiles beneath the beam and arranged in spaced relation to the bottom of the beam, said plates having 20 their upper surfaces recessed, and binding material between the bottom of the beam and rows of tiles and the bridge plates, said material seating in the recessed upper surfaces of said plates.

ROBERT ZOETTL. 25
